WITNESS:

UNITED STATES PATENT OFFICE.

ALEXANDER J. DUNLAP, OF LINCOLN, NEBRASKA.

DESIGN FOR A MARKER.

59,626.

Specification for Design.

Patented Nov. 15, 1921.

Application filed April 25, 1921. Serial No. 464,461. Term of patent 14 years.

To all whom it may concern:

Be it known that I, ALEXANDER J. DUNLAP, a citizen of the United States, residing at Lincoln, in the county of Lancaster and State of Nebraska, have invented a new, original, and ornamental Design for a Marker, of which the following is a specification, reference being had to the accompanying drawings, forming a part hereto.

The figure is a perspective view of a marker showing my new design.

I claim:—

The ornamental design for a marker as shown.

ALEXANDER J. DUNLAP.

Witness:

LAURA CASSIDY.
